EDSON L. CANNON, OF CLEVELAND HEIGHTS, OHIO, ASSIGNOR TO THE WARREN REFINING & CHEMICAL COMPANY, OF CLEVELAND, OHIO, A CORPORATION OF OHIO

LIQUID-DISPENSING RECEPTACLE

Application filed June 23, 1927. Serial No. 200,900.

- This invention relates to liquid dispensing receptacles and more particularly to receptacles such as are used by service stations for dispensing lubricating oil to automobiles.
- 5 As is well known, this oil is generally dispensed from steel drums, each equipped with a pump. Unless these drums are kept within locked rooms or buildings, there is danger that the oil may be pumped therefrom by unauthorized persons. Furthermore, as the drums are furnished by the manufacturers, it is desirable on their part that the drums so supplied shall not be refilled with oil other than that which they originally contained or 15 with oil put out by another manufacturer.
- It is the general purpose and object of this invention to provide for drums of this character an enclosure which may be conveniently attached to the tops thereof and which will 20 prevent the unauthorized dispensing of the oil therefrom as well as preventing the refilling of the drums with oil made or sold by persons other than those who furnished the drums. By reason of the attachment referred to, the drums will possess all of the advantages of storage tanks, but without the 25 large expense incurred for the purchase of such tanks. Further objects and advantages of the invention will appear hereinafter in connection with the drawings and the detailed 30 description thereof.
- In the drawings, Fig. 1 represents an elevation of a drum having my invention applied thereto, the door of the enclosure being opened; Fig. 2 a similar view, showing the door in its closed and locked position; Fig. 3 a detail in vertical section through the enclosure, the top of the drum and the top of an apron being shown in dot-and-dash lines; Fig. 4 a detail in elevation of the upper portion of the drum; Fig. 5 a view, similar to Fig. 4, showing the parts of the enclosure separated; Fig. 6 a sectional detail corresponding to the line 6—6 of Fig. 3, showing the locking lug for the door; and Fig. 7 a detail in sectional plan of the locking ring.
- Describing the parts by reference characters, 1 denotes the body of a steel drum of the type in which oil is usually dispensed, the drum being provided at the top with an out- 35 wardly extending bead, the bead being shown at 2. The head of the drum is provided with the usual oil dispensing pump, indicated at 3.
- In order to realize the objects of my invention, I apply to the top of the drum an enclosure, the same comprising generally a cylindrical wall 4 having a segmental door opening 5 therein, a cover 6, a bottom ring 10, by which the enclosure is applied and secured to the bead 2 on the drum; a segmental sliding door 7 mounted in an upper annular guide 8 and a lower annular guide 9, which are secured to the top and the bottom of the wall 4, respectively, preferably by welding. The guide 8 is provided with a cylindrical side wall 8^a by which it is welded to and within the top of the wall 4 and has its upper end bent inwardly, as shown at 8^b and then downwardly as shown at 8^c, to provide an upwardly projecting channeled guideway for the upper end 60 of the door 7. The lower guide 9 comprises a vertical cylindrical wall 9^a which is welded to the bottom of the wall 4 and has its lower end bent inwardly, as shown at 9^b, and then upwardly, as shown at 9^c, thereby providing a 65 downwardly projecting channeled guideway for the bottom edge of the door 7.
- The cover 6 is provided with a cylindrical depending wall 6^a which receives therewithin the upper end of the wall 4, being preferably 70 welded thereto.
- 10 denotes generally the locking ring by which the enclosure is applied to the top of the drum. This locking ring comprises a vertical cylindrical wall 10^a which surrounds the lower part of the wall 4, being secured to such wall by means of hangers 11 welded or otherwise suitably secured upon the outer surface of the wall and extending through suitably spaced openings in the top of the wall 75 10^a of the locking ring. By reference to Fig. 6, it will be seen that the hangers 11 are so arranged that there will be a space of about 180° between two of them, this space corresponding to the front of the enclosure and of the drum, the term "front" referring to that part of the drum and enclosure which faces the pump operator. It will be noted further that the ring 10 is split in the front portion 80 thereof, enabling it to be opened to a sufficient 85
- 50 55 60 65 70 75 80 85 90 95 100

extent to slip the said ring over the bead 2. When so applied to the bead and to the top of the drum, the enclosure may be secured in place by means of a bolt 11^a extending through 5 ears 10^d projecting outwardly from the ends of the ring 10. By setting up on the nut 11^b, the ring 10 and the enclosure carried thereby may be secured in place on top of the drum.

In order to prevent the removal of the enclosure, I provide a cage 12 pivoted at one 10 end to the ring 10 by means of a pin 13 and one or more hinge lugs 12^a and having its opposite end extended so as to engage the outer face of the ring, as shown at 12^b, the 15 extension being provided with a slot for the reception of a locking lug 10^e projecting from the ring 10, which locking lug is provided with an aperture 13 for the hasp of a padlock 14.

20 The construction and arrangement of the enclosure or hood are such that it is impossible to remove the pump for the purpose of refilling the drum without first removing the enclosure or hood; and, as the manufacturer 25 or oil company that furnishes the drum will have possession of the key to the lock 14, it will be impossible for the user of the drum to remove the pump and either refill the drum with oil supplied by someone other than such 30 manufacturer or oil company or to transfer the pump to a different drum. This protects the manufacturer or oil company against the use of the drum and pump furnished by him or it to the user for dispensing the oil of another manufacturer or oil company—thus 35 insuring that the drum and the pump so furnished shall be used only with the oil of the one who furnished it.

In order to prevent the operation of the 40 pump by unauthorized persons, the door 7 is provided. This door is shown as a segment of a cylinder, approximately 180° in extent, which is adapted to cover the segmental opening 5 in the wall 4 and which has its upper 45 and lower ends in the guides 7 and 8. This door is provided with an operating handle 7^a by means of which it may be opened and closed; also with a perforated locking lug 7^b which is adapted to be swung into contact 50 with a cooperating perforated locking lug 4^a on the wall 4. When the door is closed with the lugs 4^a and 7^b in cooperation with each other, it may be locked by means of a padlock 15, the key to which will be in the 55 possession of the user of the drum.

Another feature of my invention is the provision of the locking ring 10 with means whereby an apron or similar device may be suspended therefrom, which apron may carry 60 an inscription designating the kind or oil within the drum. 16 denotes an apron of this type, the same being preferably in the form of a segment of a cylinder, to conform to the outside of the drum 1, and being supported 65 from the ring 10 by means of hooks 17 carried

by said ring and from which hooks the apron is suspended.

By virtue of my invention, it is possible to convert an ordinary oil-dispensing drum or ordinary shipping drum into a storage tank, thereby enabling the user or dealer to leave the drum outside, merely locking up the pump by means of the door 7. It also enables the manufacturer or oil company to protect the quality of the oil dispensed from his or its drums by preventing the refilling of such drums with oil other than that furnished by him or it as well as preventing the removal of the pumps from such drums and their application to drums other than those furnished by the manufacturer or oil company.

By reason of my invention, much time and labor are saved, as it is not necessary for the user or dealer to transfer oil from drums (as by means of 5-gallon cans) to an ordinary storage tank. The user or dealer merely uses the drum in which the oil is furnished to him; applying the hood, enclosure, pump and sign thereto, and is thus in possession of an attractive storage tank, without having consumed the time and labor of transferring the oil. When the drum thus equipped has been emptied, the attachment and pump are transferred to a full drum, and this transfer of the hood and pump can be accomplished with much less labor and with much less consumption of time than are required for transferring the contents of a drum of oil to a storage tank. Furthermore, the foregoing results are realized through a construction which is simple, which is economical of production, and which is capable of convenient application to the drums or other receptacles with which it is to be associated.

Having thus described my invention, what I claim is:—

1. An enclosure for the top of a dispensing receptacle, the said enclosure comprising an expandible and contractible bottom ring 110 adapted to be secured to the top of such receptacle, the said enclosure having a wall extending above the said ring and having an opening therein and a cover, a door adapted to close the opening in the wall, means for securing the ring upon the said receptacle, and means for locking the said door in closed position.

2. An enclosure for the top of a dispensing receptacle, the said enclosure comprising 120 a split bottom ring adapted to be secured to the top of such receptacle, the said enclosure having a wall extending above the said ring and having an opening therein and a cover, a door slidably supported between the said ring and the said cover and adapted to close the opening in the wall, means for securing the ring upon the said receptacle, and means for locking the said door in closed position.

3. An enclosure for a dispensing receptacle 130

- having an outwardly projecting bead at its top, the said enclosure comprising a bottom ring, the said ring being expansible and contractible and having a seat therein for said bead, means for securing the said ring upon the said bead, a side wall secured within and projecting upwardly from the said ring, a cover at the upper end of the said wall, the said wall having an opening therethrough for access to a pump or other dispensing mechanism on the top of the receptacle, a door adapted to close the said opening, means for locking the said ring on the said bead, and means for locking the said door in closed position. 5 75
- 10 15 4. An enclosure for a dispensing receptacle having an outwardly projecting bead at its top, the said enclosure comprising a bottom ring, the said ring being divided and having a seat therein for said bead, and means adjustably connecting the ends of the said ring to secure the ring upon the said bead, a side wall secured within and projecting upwardly from the said ring, a cover at the upper end of the said wall, the said wall having an opening therethrough for access to a pump or other dispensing mechanism on the top of the receptacle, said enclosure also comprising a door adapted to close the said opening, a shield for the means connecting the ends of said ring, means for locking the said shield in protecting position, and means for locking the said door in closed position. 20 25 30 80 85 90 95
- 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945
5. An enclosure for a receptacle having a bead at its top, the said enclosure comprising a bottom ring having a seat for the said bead, the ring being divided whereby it may be opened to receive the bead and may be closed about the same, means for locking the ring in closed position, a cylindrical wall carried by said ring and having an opening therein, a cover secured to said wall, upper and lower annular channeled guides carried by and within the upper and lower ends of the said wall, respectively, a segmental door mounted in said guides and adapted to slide in the guides across the opening in said wall, and means for locking the said door in closed position. 100 105 110 115 120 125
6. An enclosure for a receptacle having a bead at its top, the said enclosure comprising a bottom ring having a seat for the said bead, the ring being expansible and contractible whereby it may receive the bead and be tightened about the same, a wall carried by said ring and having an opening therein, a cover secured to said wall, upper and lower guides carried by the upper and lower ends of the said wall, respectively, a door mounted in said guides and adapted to slide across the opening in said wall, and means for locking the said door in closed position. 115 120 125
7. An enclosure for the top of a dispensing receptacle, the said enclosure comprising an expansible and contractible bottom
